COMBINATION HANDLE AND LOCKING
DEVICE FOR DOORSHeward G. Stoner, Pittsburgh, Pa., assignor to
Pittsburgh Plate Glass Company, a corporation

Application May 25, 1938, Serial No. 209,927

5 Claims. (Cl. 70—121)

The present invention relates to fastening devices for doors and it has particular relation to fastening devices for double doors consisting essentially of rimless plates of tempered glass.

5 One object of the invention is to provide a securing device of the foregoing type which obstructs the surface of the glass to a minimum degree, and which can easily and economically be mounted in the doors.

10 A second object of the invention is to provide a securing device which can be employed to lock together the edges of a pair of doors without the use of keepers or bolts requiring mortises in the edges of the glass.

15 These and other objects will be apparent from consideration of the following specification and the appended claims.

It has been proposed to construct doors for buildings, of single heavy panels of glass to which 20 the hinges were directly secured without interposition of a framework. For such constructions, glass panels which have been tempered by heating them to 1100 or 1200° F. and then suddenly cooling them with a blast of air or by 25 plunging them in oil are particularly satisfactory. Glass so treated is far stronger than ordinary annealed glass and is capable of withstanding the stresses exerted by the hinges. If the surface is broken, they automatically shatter into 30 fragments so small as to create but little hazard to persons or objects struck by them.

Doors constructed of sheets of glass are of striking brilliancy, strongly suggestive of single massive plates of crystal, and to maintain this 35 effect it is desirable that the hardware employed therewith occupy a minimum area and in general harmonize with the panels. The difficulty of providing satisfactory hardware is increased by the peculiarities of the glass which make it 40 difficult to form holes and openings therein, for reception of parts of the hardware.

In accordance with the provisions of the present invention the foregoing difficulties are overcome by provision of door handles approximately of C shape, the intermediate portions of which rotate in openings in the panels in such manner that they can be used either as handles or can be rotated to extend beyond the edge of the panel to engage a surface such as the edge 50 of an adjacent panel. The handles are thus made to include the function of locking bolts and the necessity of forming openings in the edges of the glass to receive transversely sliding and locking bolts of conventional type is obviated. 55 Simplification of installation and perfect har-

mony between the glass panel and the hardware are thus attained.

For a better understanding of the invention reference may now be had to the accompanying drawings in which like numerals refer to like parts throughout.

Fig. 1 is a fragmentary elevational view of a building wall in which is installed a pair of swinging doors that embody the principles of the present invention.

Figs. 2 and 3 are fragmentary elevational views showing the combination handles and locking bars on a larger scale, respectively, in position to act as latches or locks and as simple handle bars.

Fig. 4 is a fragmentary view showing a portion 10 of the edge of a door panel in which the handles constituting the subject matter of the present invention are installed.

Fig. 5 is a fragmentary edge view of the door panel with portions sectioned away to show the 20 interior of a locking mechanism that may be employed.

In practicing the invention, a building wall 10 is formed with an opening 11 in which door panels 12 are secured by means of hinges 13.

25 The specific construction of the hinges is not a feature of the present invention and need not be described.

The doors, preferably devoid of any sash-like framework, consist of massive slabs of glass of 30 a thickness of at least one-fourth inch and are usually of a thickness of one-half to one and one-half inches. The slabs are first formed by casting, or drawing, or by any other convenient manner and after they have been annealed they 35 may, if desired, be polished. Any notches or openings required may be cut or sand-blasted out before or after the polishing operation, but before tempering. They are tempered by heating the preformed slabs to about 1100 or 1200° 40 F. and then cooling them quickly, e. g., by plunging them into oil or by exposure to a blast of air.

It is important that the openings in the glass be round or at least have rounded corners, the 45 radii of curvature being not less than one-half the thickness of the glass.

The combined handle and locking structure for the panels comprises members 14, approximately of C shape (see Fig. 4) formed of two opposed rods or tubes 16 and 17. These members have their respective free ends 18 and 19 provided with rubber cushions 20 and inwardly bent to such degree as to allow only a slight clearance for the panels 12. The opposite ends of members 16 and 17 are also inwardly bent 55

and the portion 21 of the former is welded or formed integrally with a bearing portion which, in the form shown, comprises a circular block 22 of about the same thickness as the glass plate.

- 5 5 This portion may rotate in any suitable female bearing or journal, e. g., a sleeve which may, as shown, be a block 23 of the same thickness as the glass and having an opening for the reception of the portion 22. The block is mounted in 10 opening 24 in panel 12, the edges of the opening being protected by a packing 26 of more or less plastic or adhesive material to prevent direct contact of metal and glass.

Block 23 is secured from displacement by 15 means of clamping plates 27 and 28, having openings 29 and 31 pierced therein for the admission of handles 16 and 17. One of the plates, e. g. 27, may be secured to block 23 by welding while the other is releasably secured, for example by means of screws 32 shown in Figs. 2 and 3. Screws may even be employed to secure both plates, if so desired.

Handle 17 may be secured to block 22 by welding, or as shown in Fig. 5, the rear face of the 25 block may be formed with a lug 33 adapted to fit within a notch in a disc 34, to which the extremity of the handle 17 is welded or otherwise secured. When the structure is assembled, plate 28 secures the key from outward displacement.

30 In order to secure the handles 16 and 17 in position to act as simple latches, plates 27 or 28 may be provided with lugs 35 and 36, engaging lugs 35a and 36a upon the portions 21 which function as stops to limit the extremity of their 35 arc of swing to the position shown in Fig. 2.

If it is desired, positively to lock the handles from displacement, suitable locking mechanism may be provided. The locking mechanism may be housed in block 23 and the notches formed in 40 bearing 22. For example, the lock may be of the "tumbler" type and include a lock cylinder 37, corresponding substantially to that in an ordinary night latch. The cylinder which is disposed in openings 38 and 39, formed respectively in block 45 23 and plates 27 and 28, includes clamping plates 41 and 42. These are secured together by studs 43 welded to plate 41, and by screws 44 threaded through plate 42 into the studs.

The internal mechanism of the lock is not a 50 part of the present invention, and since it is well understood by those skilled in the art, it is not deemed necessary to describe it in detail. It includes suitable tumblers or equivalent devices (not shown) disposed in a rotatable barrel 55 46, best shown in Fig. 2 and operated by means of key 47, which is inserted through key hole 48 in the end of the barrel.

The barrel 46 at its inner extremity carries a pawl 51 designed to engage a lug 52 upon the side 60 of a locking bolt 53 for the purpose of retracting the latter. The bolt at its upper extremity is provided with an enlarged portion 54, sliding in a passageway 56 in block 23. Notches 57 are formed in the outer periphery of bearing 22 in position to be engaged by the extremity of bolt 53 to lock the handles 16 and 17 in either of the 65 positions shown in Figs. 2 and 3.

The bolts 53 may also be actuated from the rear face of the door by a thumb latch mechanism. This mechanism comprises a thumb knob 70 58 attached to a stem 59 which rotates in an opening in plate 42 and at its inner extremity attaches to barrel 46 to actuate the latter independently of the key.

75 Assembly and operation of the mechanism is

self-evident. Assuming that the openings 24 have been provided in the doors 12, and that the latter have been hung. The packings 24 are placed about the edges of the openings and blocks 23, having bolts 53 in position in passages 56, are secured in the latter. Subsequently plates 27 are slid upon handles 16 and bearings 22 are slipped into position in blocks 23. The handles 17 having plates 28 thereupon are then secured by setting discs 34 upon bearings 22. By 10 threading screws 32 through the plates into blocks 23, the various parts are secured from displacement. The next operation of assembly involves securing cylinders 37 in place in openings 38 and 39, and then securing plates 42 by means 15 of screws 44. Finally knobs 58 are secured to stems 59 and assembly is complete.

Where the bars 16 and 17 are to function as simple handles they are rotated to vertical position, as shown in Fig. 3 and secured in that position by actuation of bolts 53 to engage the appropriate notches 57 in the members 23.

If the bars are to function as latches or locks, they are rotated to the diagonal positions shown in Fig. 2 and are there secured by the lock bolt 25 in notches 57.

The construction is extremely simple and compact and requires but a single simple opening in the glass, which opening is easily formed by sandblasting. No mortise in the edge of the glass for 30 the bolt is required.

The embodiment of the invention herein shown is merely exemplary, numerous modifications may be made therein without departure from the spirit or scope of the claims.

What I claim is:

1. A latching device for double swinging doors of tempered glass comprising a block adapted to be mounted in an opening in a door, the block having a circular opening extending therethrough, a rotatable block mounted in the latter opening, handles rigidly secured to the latter block and being laterally bent to provide a member of C shape, the ends of which are adapted to engage upon opposite sides of a second door, and means to secure the first-mentioned block in place in the opening in the door, said means comprising a plate secured to the block and providing a flange engaging the portions of the door adjacent the opening, a second plate secured to the opposite side of the block by means of a screw fastening and providing a second flange engaging the remaining side of the door, said plates having openings therein through which the handles extend the rotatable block being formed with notches about its periphery and detent means disposed in the first-mentioned block and selectively engaging the notches to secure the rotatable block from rotation in a predetermined position.

2. A combined handle and securing device for double doors, which doors comprise two panels, each panel being mounted to swing in a doorway about its edge, remote with respect to the other panel, said devices comprising a pair of handle members, one for each panel, and being approximately of C shape, the intermediate portion of each member being journaled in a bearing block disposed in an opening formed in its corresponding panel, each member having its extremities projecting from opposite sides of its panel across the edge of the adjacent panel and constituting locking means securing the panels against rotation and being rotatable in its bearing block to a position out of its locking relation.

3. A construction as defined in claim 2 in which means is provided selectively to secure the handle members from rotation when functioning either as a lock or when rotated to a position out of locking relation.

4. A construction as defined in claim 2 in which notches are formed in the intermediate portions of the rotatable members and movable detents are provided in the bearings adapted to engage the notches selectively to secure the rotatable members in predetermined position.

5. A latch construction for a door panel, which panel has an opening formed directly therethrough adjacent to one edge, the edge being free to swing about the opposite edge as an axis, said latch construction comprising a mem-

ber approximately of C shape, the intermediate portion of which is journaled in a bearing block in the opening, the bearing block being secured by plates attached thereto and clamping opposite sides of the panel, the member being rotatable from an approximately vertical position in which it acts as a handle, to position in which it engages upon opposite sides of a second panel adjacent to the swinging edge to lock the door panel in closed position, the intermediate portion of the member being notched and movable detent means housed in the bearing block selective to engage the notches and secure the member in either of its positions of adjustment.

15

HOWARD G. STONER.
